(57) CLAIM

I claim the ornamental design for a digital meter case and lens assembly, as shown and described.

DESCRIPTION

FIG. 1 is a perspective view of the digital meter;

FIG. 2 is a front plan view thereof;

FIG. 3 is a rear plan view thereof;

FIG. 4 is a top plan view thereof;

FIG. 5 is a bottom plan view thereof;

FIG. 6 is a right side plan view thereof; and,

FIG. 7 is a left side plan view thereof.
